WILLIAM F. HENDRY, OF OSSINING, NEW YORK, ASSIGNOR TO MANHATTAN ELECTRICAL SUPPLY COMPANY, INC., A CORPORATION OF MASSACHUSETTS.

TRANSFORMER-CORE STRUCTURE.

Application filed June 22, 1927. Serial No. 200,674.

This invention relates to core structures for transformers and relates more particularly to a core structure for a constant current transformer.

5 An object of the invention is the provision of a laminated core for a constant current transformer, consisting of a plurality of differently shaped core elements so formed as to be easily fitted together upon assembly 10 of the core unit.

Another object is to so construct the core elements of a constant current transformer that the core and transformer coils can be quickly and cheaply assembled.

15 Various types of transformers are now known wherein the core is constructed of a plurality of thin sheets of magnetic material placed one on top of the other in overlapping relation. Many of these transformers 20 consist of two separate windings mounted on a closed laminated core. These cores are roughly of the form of a square or rectangle and are built up of a plurality of straight pieces of thin iron or similar material, several 25 pieces of which form each leg of core and all of the legs of which are so constructed as to dovetail together with the other legs.

In the construction of constant current 30 transformers and other transformers wherein the core consists of an A-shaped section, it is of course possible to make a core consisting of a plurality of straight pieces mutually interlocked in the manner above mentioned, 35 but this process involves considerable expense and requires careful assembling of the transformer.

According to my invention a constant current transformer may be conveniently constructed having a single coil primary and a double coil secondary winding, all of the 40 said windings being mounted on a closed magnetic core having a magnetic shunt consisting of a pair of legs extending out from the core in such a manner as to tend to shunt 45 the magnetic circuit of the primary core. For ease of construction of such a transformer, I have provided a core which is built up of a plurality of pairs of differently 50 shaped elements which fit together in such a manner as to form a substantially A-shaped core. In the finished transformer the primary winding is mounted on the cross bar of the A, two secondary windings are

55 mounted on the two legs extended upwardly from the cross bar of the A and the magnetic shunt is comprised of the two lower legs of the A. Each pair of core elements consists of a J-shaped section and an L-shaped or a 60 right angled shaped section. These two sections are fitted together with their edges in contact in such a manner that one leg of the L extends from the short upturned portion of the J across to an intermediate point of the long upturned portion of the J and the 65 other leg of the L-shaped portion extends upwardly away from the short upturned portion of the J. Such a construction as this allows a core to be quickly and easily 70 constructed, as it is necessary merely to hold the three coil sections in a jig and insert the core sections alternately to build up a core.

Referring to the drawings, Fig. 1 illustrates the first step in assembling a core for a transformer, in accordance with my 75 invention; Fig. 2 illustrates the core after the completion of the step shown in Fig. 1; Fig. 3 illustrates the second step in assembling the core; Fig. 4 illustrates the core after the completion of the step shown in 80 Fig. 3.

Reference numeral 1 indicates the primary winding of the transformer; 2, one coil of the secondary winding; 3, the other coil of the secondary winding; 4, a J-shaped 85 section of the core; and 5, an L or right angled section of the core.

In assembling the transformer the three coil windings are held in the position shown in Fig. 1 by suitable means, with the two 90 secondary coils placed parallel to each other a suitable distance apart and the primary coil placed at right angles to and between the axes of the secondary coils and spaced slightly from the ends of the said coils. 95 With the coils so placed, one of the J-shaped sections of the core is thrust through the two secondary coils in the direction illustrated by the arrow in Fig. 1. Then an L shaped section is thrust in through the primary coil in the direction also illustrated by an arrow. When the two core sections have been thrust through the windings, the partially formed core has the form shown in Fig. 2. The next step as shown in Fig. 100 3 is to thrust through the two secondary coils another J-shaped section, 6, which is 105 in the reversed position from the first

J-shaped section, then another L-shaped section, 7, is thrust through the primary coil in the opposite direction to the first L-shaped direction, which leaves the core in the form shown in Fig. 4. This process is continued by the insertion of J and L shaped sections alternately in the manner just described until the core attains the desired thickness.

The secondary winding is made in two portions in order to keep the overall dimensions and weight of the transformer as small as possible, thus making a smaller transformer than would be possible if the secondary coil were made in one section. It will be obvious that with different transformers the length of the open legs should be adjusted to give the desired results, in the manner well known to the art.

While I have described my invention as applied to a constant current transformer, it is to be understood that the invention is equally applicable to the other types of transformers wherein a core of this shape is desirable.

It will be obvious to those skilled in the art that the present disclosure is intended merely to illustrate one form which my invention may take and that the invention is capable of a wide variety of modifications and adaptations without a departure from

the spirit of the invention as set forth in the appended claims.

What I claim is:

1. A constant current transformer having a single coil primary and a double coil secondary, the core of said transformer comprising a J-shaped section and an L-shaped section, the secondary coils being positioned on the two upturned legs of the J-shaped section adjacent the closed end thereof, the primary coil being positioned on one leg of the L-shaped section and the two core sections being put together in A-shape, with the leg of the L-shaped section which bears the primary coil extending between the two upturned portions of the J-shaped section. 35 40 45

2. A constant current transformer having a core made up of J-shaped sections and L-shaped sections, a primary coil positioned on one leg of the L-shaped section, a secondary coil positioned on one of the upturned legs of the J-shaped section, the two core sections being assembled in H-shape with the leg of the L-shaped section bearing the primary coil extending between the upturned portions of the J-shaped section. 50 55

In testimony whereof, I have signed my name to this specification this 17th day of June, 1927.

WILLIAM F. HENDRY.
